UNITED STATES PATENT OFFICE

ARMIN ELMENDORF, OF CHICAGO, ILLINOIS, ASSIGNOR TO THE FLEXWOOD COMPANY, OF CHICAGO, ILLINOIS, A CORPORATION OF DELAWARE

METHOD OF AND MEANS FOR TREATING VENEERED SHEETS

Application filed April 10, 1929. Serial No. 353,952.

In my prior application, Serial No. 334,-
865, filed January 24, 1929, I have disclosed a
novel material comprising a flexible backing
faced with thin wood veneer whose structure
has been broken down to such an extent that
5 the veneer will have no tendency, when dry,
to curl up. The present invention has for
its object to make it possible rapidly and at
a small cost to treat the sheet so that the
veneer will possess the aforesaid character-
istic.

The treatment of the veneer to place it in
a condition such that it will have no tend-
ency to curl under moisture and tempera-
15 ture changes or, in other words, to render it
limp, because of the frail character of the
veneer, can best be effected after the veneer
has been glued to its backing. Therefore,
viewed in one of its aspects, the present in-
20 vention may be said to have for its object
rapidly and economically to treat a flexible
material faced with thin wood veneer so as
to render the veneer limp or, in other words,
destroy its capacity for curling, without
25 marring the appearance of the surface of the
veneer when the product is laid flat.

In carrying out my invention, beginning
at one end of the sheet, I stress the exposed
faces of successive narrow strips extending
30 in the general direction of the grain, one
after another, past the rupture point; bring-
ing about a progressive partial disintegra-
tion of the veneer throughout the entire area
35 of the sheet. This may conveniently be done
by bending the sheet over an edge extending
in the general direction of the grain of the
veneer, with the backing next to the edge,
and producing a relative movement between
40 the sheet and the edge, across the grain. The
face of the veneer may be left exposed dur-
ing the process, but a more uniform effect
is obtained by maintaining on the face of
45 the veneer, at the bend, a pressure that is
more or less radial over the entire bent area.
Therefore, viewed in one of its aspects, my
invention may be said to comprise a novel
method of treating the material in question,
50 whereby a yielding pressure will be main-
tained on the face of each narrow section of

veneer while the latter is undergoing partial
disintegration.

Viewed in another of its aspects, the pres-
ent invention may be said to have for its ob-
ject to produce a simple and novel machine
55 by means of which a sheet composed of a
flexible backing and a facing of wood veneer
may be successfully treated, at a low cost, to
render the veneer limp.

The various features of novelty whereby
my invention is characterized will herein-
after be pointed out with particularity in the
claims; but, for a full understanding of my
invention and of its objects and advantages,
60 reference may be had to the following de-
tailed description taken in connection with
the accompanying drawings, wherein:

Figure 1 is a front elevation of a ma-
chine for carrying out my invention, parts
being broken away; Fig. 2 is an end view of
70 the machine; Fig. 3 is a section on line 3—3
of Fig. 1; Fig. 4 is a section on the same
plane as Fig. 3, but on a larger scale, show-
ing a fragment of the machine; Fig. 5 is a
75 view on an enlarged scale showing more or
less diagrammatically the manner in which
the sheet is stressed; and Fig. 6 is an end
view of a modified form of the machine.

Referring to Fig. 5, A represents a sheet
80 of strong flexible material faced with a layer
B of wood veneer. C is a cushion, preferably
of rubber. E is a blade-like bar that may
be called an edge. If the sheet, consisting
of the united layers A and B, with the grain
85 of the wood extending transversely of the
sheet, is laid against the cushion with the
veneer next to the latter, and the cushion and
the edge are moved relatively toward each
other so that the cushion must yield, a com-
paratively sharp bend will be formed in the
90 sheet. In other words, the sheet will be
bent more or less sharply over the edge, caus-
ing the face of the veneer, extending entire-
ly across the sheet, to be stressed across the
95 grain beyond the rupture point. If the
sheet were simply forcibly bent over the edge
without the presence of the cushion, the veneer
might simply split wide open along a more
or less irregular line, continuous or other-
100 wise, along the grain. However, my purpose

is eventually to produce numerous narrow brakes closely spaced; it being immaterial whether the veneer be split through its entire thickness or only for a fraction of its thickness inwardly from the outer face. By providing a cushion which, while yieldable, offers considerable resistance to compression, the face of the veneer throughout the area that curves over the edge is yieldingly held and is subjected to pressures more or less normal to the surface. The result is that the veneer will split in such a manner as not to form wide cracks. If now the sheet is moved lengthwise a short distance, either while the edge is held back clear of the sheet or while it is pressing the sheet into the cushion, the bend or wave in the sheet will be shifted, bringing a fresh area opposite the edge. Thus, if the edge has remained in its working position or is brought back into the position, this new area will be ruptured. Assuming that the sheet is being moved upwardly in Fig. 5, the area opposite the edge will have the veneer face visibly split as indicated by the more or less radial lines *b*. As the sheet passes upwardly and straightens out again, the breaks in the veneer will close so as not to be visible.

In Figs. 1 to 4 there is shown a machine for carrying out the process just described, by means of a blade or edge that moves rapidly between an idle and a working position. Furthermore, I have provided two blades or edges so that the veneer may be said to be processed twice.

Referring to Figs. 1 to 4 of the drawings, 1 and 2 represent two end frame members, and 3 a top connecting piece between the same. Between the ends of the frame and at some distance below the top member 3, is a roll 4 covered with a cushioning layer C of rubber. Behind the roll 4 are two feed rolls 5 and 6. In front of the roll 4 is another pair of feed rolls 7 and 8. The sheet to be operated upon, indicated at AB, passes between the feed rolls 5 and 6, over the top of the roll 4 and down between the feed rolls 7 and 8.

A horizontal shaft 9, parallel with the several rolls, is journaled in suitable brackets or hangers 10 on the underside of the top frame member 3. Below the shaft 9 are two parallel shafts 11 and 12, one on each side of a vertical plane containing the long axis of the shaft 9. Fixed to the shafts 11 and 12 are L-shaped brackets each having an upper arm 13 and a lower arm 14. The brackets on one shaft are arranged opposite those on the other shaft. The upper end of each upper bracket arm is fastened to the upper end of the corresponding opposite arm by a spring 15; the parts being so proportioned that the springs lie above the shaft 9. The lower arms of each set of brackets are connected together by bars or blades E corresponding

to the edge E previously referred to. On the shaft 9 are cams 16 engaged by cam rollers 17 on the upper arms of the brackets. The parts are so proportioned that when the cams are in the positions shown in Figs. 3 and 4, they press the upper arms of each pair of brackets apart, forcing the members E down into the cushioning layer on the underlying roll. However, when the shaft 9 is turned through an angle of 180°, the springs come into play, drawing together the upper ends of each pair of brackets and raising the members E from the roll.

It will be seen that if the shaft 9 is rotated rapidly, while the roll 4 is turned slowly, the work will be carried first under one edge member and then under the other, being progressively waved under the first edge member and then again under the second. The surface of the veneer will be broken into narrow filaments as the sheet travels under the first edge. By properly adjusting the edge members, the second edge member may be caused to act largely on the narrow filaments produced by the first, breaking such filaments into still narrower ones.

The shaft 9 and the roll 4 may be driven in any suitable way. In the arrangement shown, the shaft 9 is driven directly from a motor 18 through a belt 19. On one end of the shaft 9 is a worm 20 meshing with a worm wheel 21 on a vertical shaft 22. On the lower end of the shaft 22 is a worm 23 meshing with a worm wheel 24 on the shaft 25 that carries the roll 8. The rolls 7 and 8 are caused to rotate in unison with each other and in opposite directions, by means of inter-meshing spur gears 26 and 27, on the roller shafts 25 and 28 respectively. It will thus be seen that when the motor is running, the rolls 7 and 8 will serve slowly to draw the sheet over the roll 4, the sheet serving as a belt to drive the latter roll. The shaft 9 is rotating at a very high speed compared to that of the feed rolls, so that the edge members strike rapid blows on the work. Since the sheet cannot move very far between blows of the edge members, the lines across the sheet on which the blows are struck will be closely spaced.

The shaft 30 that carries the main roll 4 is preferably mounted in vertically adjustable bearings 31, thereby permitting the roll to be adjusted up and down in order to vary the depth to which the sheet is pressed into the cushion surface of the roll by the edge members.

In Fig. 6 I have illustrated a machine in which the edge member is stationary. Referring to this figure, 35 represents a suitable frame structure in the top of which is mounted a roll 36 having a cushioning layer C covering the same. Below and on opposite sides of the roll 36 are rolls 37, 37. The sheet A B passes up under the left hand roll 37, across the top of the roll 36 and down underneath 38

the right hand roll 37. Two bars or edge members E are fixed to the frame on opposite sides of the roll 36; the distance between the members E being less than the overall diameter of the cushioned roll, so that these members press into the cushions. Consequently the sheet, in order to pass by the edge members, must take a sharp bend at each edge member. In other words, as the sheet is drawn ahead there is formed therein at the first edge member a wave that travels progressively along the sheet. The process is repeated at the second edge member.

I do not wish to limit myself to any particular degree of fineness in the disintegration of the veneer because for some uses the breaks may be farther apart than for others. It is possible, however, by making the radius of an edge over which the sheet is drawn small, to produce breaks that will be an average distance of a thirty-second of an inch or less apart. By passing the sheet successively over two such edges a very complete breaking down of the veneer may be effected without, however leaving any visible breaks in the surface when the sheet is laid flat.

I claim:—

1. The method of making pliable a sheet composed of a flexible backing faced with wood veneer, which consists in partially disintegrating the veneer by tearing or splitting the same along the grain to divide the face thereof into many narrow filaments.

2. The method of treating a sheet composed of a flexible backing faced with wood veneer, which consists in laying the backing against an edge extending in the general direction of the grain in the wood and placing a rubber cushion against the veneer, and applying sufficient pressure to cause rubber to be compressed and bend the sheet over said edge.

3. The method of treating a sheet composed of a flexible backing faced with wood veneer, which consists in moving the sheet past an edge extending in the general direction of the grain in the wood and lying behind the backing, and pressing a yieldable cushion against the veneer opposite said edge in order forcibly to bend the sheet over said edge.

4. The method of treating a sheet composed of a flexible backing faced with wood veneer, which consists in laying the veneer side of the sheet against a cushion, and progressively waving the sheet along lines extending in the general direction of the grain by pressing it forcibly into the cushion.

5. The method of treating a sheet composed of a flexible backing faced with wood veneer, which consists in moving it transversely of the grain of the wood between an overlying cushion and an underlying edge extending in the general direction of the grain, and causing said edge forcibly to press one narrow strip after another into the cushion far enough to stress the face of the veneer past the rupture point.

ion far enough to stress the veneer past the rupture point.

6. The method of treating a sheet composed of a flexible backing faced with wood veneer, which consists in laying the sheet, face down, on and moving it in unison with a rotating roll covered with yieldable rubber and extending in the general direction of the grain in the veneer, and forcibly pressing the sheet into the rubber along a line extending in the general direction of the grain as it is carried past a given point.

7. The method of treating a sheet composed of a flexible backing faced with wood veneer, which consists in laying the sheet, face down, on and moving it in unison with a rotating roll covered with yieldable rubber and extending in the general direction of the grain in the veneer, and pressing an edge extending in the general direction of the grain against the sheet so as to bend it and force it into the rubber in passing a given point.

8. In a machine for the purpose specified, a roll having a cushioned surface, and an edge member beside and parallel with the roll for forcing a sheet into the roll as the sheet is carried along with the roll.

9. In a machine of the character described, a roll covered with yieldable rubber, and means for forcing a flexible sheet carried along with the roll into the roll along a line extending lengthwise of the roll as the sheet moves past a given point.

10. In a machine of the character described, a roll covered with a cushion in the form of rubber or the like, a member having an edge extending lengthwise of the roll, and means for actuating said member so as to press into the cushion a sheet movable with the roll.

11. In a machine of the character described, a roll covered with a cushion in the form of rubber or the like, a member having an edge extending lengthwise of the roll, means for drawing a sheet over the roll between the roll and said member, and means for rapidly operating said member from and toward the roll, the parts being so proportioned that said member forces the sheet into the cushion when said member is moved toward the roll.

12. The method of treating a sheet composed of a flexible backing faced with wood veneer, which consists in moving it transversely of the grain of the wood between an overlying cushion and an underlying edge extending in the general direction of the grain, and causing said edge forcibly to press one narrow strip after another into the cushion far enough to stress the face of the veneer past the rupture point.

13. The method of treating a sheet composed of a flexible backing faced with wood veneer, which consists in laying the sheet, face down, on and moving it in unison with a rotating roll covered with a yielding cushion and extending in the general direction of the

the grain in the veneer, and forcibly pressing the sheet into the cushion along a line extending in the general direction of the grain as it is carried past a given point.

- 5 14. In a machine of the character described, a yieldable cushion, an edge member parallel thereto, and means to produce relative movements between the said member and the cushion to cause a flexible sheet lying on the cushion to travel past said member and be pressed into the cushion thereby so as progressively to wave the sheet as the sheet and said member move relatively to each other lengthwise of the sheet.
- 10 15. In a machine of the character described, a roll covered with yieldable material, and means for forcing a flexible sheet carried along with the roll into the roll along a line extending lengthwise of the roll as the sheet moves past a given point.
- 20 16. In testimony whereof, I sign this specification.

ARMIN ELMENDORF.
